UNITED STATES PATENT OFFICE.

ERIK JULIUS LEWINSKY AND ANDERS VILHELM VIGGO LEWINSKY, OF COPENHAGEN,
DENMARK.

REGULATING DEVICE FOR CENTRAL HEATING INSTALLATIONS.

Application filed April 6, 1926, Serial No. 100,194, and in Denmark November 18, 1924.

In central-heating installations consisting of a water-boiler and an expansion-receiver, mutually connected by a rising-pipe and by a series of return-pipes, an arrangement for regulating the supply of combustion air to the fire place of the water-boiler is furnished, which arrangement usually consists of an organ able to be influenced by the temperature of the boiler water in such a manner that the movements caused by its expansion or contraction are transferred to the damper or valve for air supply.

Such regulators either are based on the longitudinal variations of a pipe inserted between the outlet- and inlet-pipes of the boiler, or on the expansion of a fluid enclosed in a casing.

The regulating pipes of the first group must be rather long, if their longitudinal variations by small alterations of temperature shall be sufficiently large, and during their mounting the heating installation must be emptied from water, and the arrangements of the second group cannot be relied upon after the use of some time.

Our invention relates to a regulating device which is acted upon directly by the temperature of the boiler water, as the arrangements of the former group, and at the same time is placed directly on the boiler, as the arrangements of the latter group of known regulators.

Our invention is illustrated in the accompanying drawing, in which

Figure 1 shows the regulating device in side-view;

Fig. 2 the same in front-view; and

Fig. 3 the same in vertical section.

According to our invention a pipe 1 is placed in or near the top of the boiler and furnished with a cover 2 having an air valve 3. The pipe 1 surrounds a concentric inner pipe 4, the upper part of which does not reach quite up to the cover 2, while its lower end projects with a piece into the boiler. The larger this piece is, the more sensitive becomes the regulating device. Connected to the upper end of the outer pipe 1 is the upper end 5 of a casing 6. The lower end 7 of casing 6 is open and loosely surrounds the pipe 1.

The lower end 7 of casing 6 has knife-edges 8 directed downward and lodged in a fork-shaped piece 10 of a lever 9. Under the branches of the said fork 10 is a firm plate

11 having upwardly directed knife-edges 12, the knife-edges 8 and 12 being displaced from one another. The lever 9 further has a downwardly directed knife-edge 13, being displaced with respect to a knife-edge 15 60 lodged in an arm 14, and carried by a rod 16, which is connected with the damper or air valve of the fire-place.

Our regulating device acts in the following manner:

By alterations of temperature in the boiler water a circulation in the water-filled pipe 1, caused by the length of the inner return pipe, will take place indicated by arrows, and thus the outer pipe will always have 70 the temperature of the water, and will change its length owing to the alteration of the temperature. The movement caused by this alteration is transmitted to the casing 6, so that the lever 9 will be lifted or sunk, 75 which movement again will bring about a swinging of the rod 16, to the end of which the damper or valve in well-known manner is connected by means of a chain or the like.

Our device may be made in relatively 80 small dimensions, an alteration of a millimeter of the length of the pipe 1 causing a considerable oscillation of the rod 16, which is counterbalanced in such a manner, that the damper has overweight.

The regulating device can be screwed on water filled boilers of every kind, and no special pipe-connections or other mountings are needed.

For the knife-edge 13 two notches are furnished in the rod 16, so that it, by means of an adjusting screw, can be shifted according to the connection of the rod with the damper.

Having thus described our invention, we claim:

In regulating devices for central-heating installations, in which a member expanding and contracting by alterations of temperature adjusts a damper for air supply by means of a lever- and knife-edge-connection, the combination, with a boiler, of an outer pipe mounted at the top of the boiler and communicating at the lower end with the interior of the same, an inner return pipe surrounded by and separated from the said 100 outer pipe and projecting into the boiler to effect a circulation of water through the pipes, a cover placed at the upper end of the said outer pipe, a casing surrounding the said pipes and connected to the outer pipe, 105 110
